UNITED STATES PATENT OFFICE.

JOHN K. MC LAUGHLIN, OF PHILADELPHIA, PENNSYLVANIA, ASSIGNOR TO
THE BUCKWALTER STOVE COMPANY, OF PENNSYLVANIA.

DESIGN FOR A HEATING-STOVE.

SPECIFICATION forming part of Design No. 32,409, dated March 27, 1900.

Application filed February 28, 1900. Serial No. 6,880. Term of patent 7 years.

To all whom it may concern:

Be it known that I, JOHN K. MC LAUGHLIN, a citizen of the United States, residing in the ~~City~~ and county of Philadelphia, State of Pennsylvania, have invented and produced a new and original Design for a Heating-Stove, of which the following is a specification, reference being had to the accompanying drawing, forming part thereof.

The leading features of my design for a heating-stove are, first, a dome or scrollwork and a rim beneath the same; next, a door with a scalloped damper thereon; next, a fender with open scrolls on the body of the stove, and, finally, a base with scalloped dampers thereon.

The figure represents a perspective view of a stove embodying my design.

In the drawing, A designates the dome of the stove, the same consisting of the upper and lower sections B and C, with scrolls D thereon.

E designates a rim at the base of the dome,

and F designates the cylinder or body of the same, the latter having the doors G and H, which, with the frame J thereof, have scrolls 25 K L thereon.

M designates a damper on the door H, the same having a scalloped periphery.

N designates a fender on the lower portion of the body of the stove, the same being ogee-shaped and having open scrolls P thereon.

Q designates the base of the stove, the same having a door R, on which are the dampers S, whose peripheries are scalloped. On said base 30 Q are scrolls T.

Having thus described my invention, what I claim as new, and desire to secure by Letters Patent, is—

The design for a heating-stove substantially as shown and described.

JOHN K. MC LAUGHLIN.
